[57] CLAIM

The ornamental design of the bowling alley bounce board, as shown.

DESCRIPTION

FIG. 1 is a perspective view illustrating the top of a bowling alley bounce board in accordance with the present invention;

FIG. 2 is a perspective view illustrating the bowling alley bounce board as shown in FIG. 1 as seen from a position below the bounce board;

FIG. 3 is a top plan view of the bowling alley bounce board shown in FIGS. 1 and 2;

FIG. 4 is a bottom plan view of a bowling alley bounce board in accordance with the invention;

FIG. 5 is a first side-elevational view of the bowling alley bounce board according to the invention;

FIG. 6 is a side view of a bowling alley bounce board according to the invention taken from the opposite side of that shown in FIG. 5;

FIG. 7 is an end view of a bowling alley bounce board taken from one end of the bounce board; and,

FIG. 8 is an end view of the bounce board shown in FIG. 7 but taken from the opposite end.

FIG. 1

FIG. 3
